UNITED STATES PATENT OFFICE

127,740

DESIGN FOR A SCARF HOLDER OR SIMILAR ARTICLE

Guy H. Montmartin, New York, N. Y.

Application April 16, 1941, Serial No. 100,400

Term of patent 3½ years

To all whom it may concern:

Be it known that I, Guy H. Montmartin, a citizen of France, residing in city of New York, county of New York, and State of New York, have invented a new, original, and ornamental Design for a Scarf Holder or Similar Article, of which the following is a specification, reference being had to the accompanying drawing, forming part thereof.

Fig. 1 is a plan view of a scarf holder or similar article showing my new design.

Fig. 2 is an edge view thereof.

I claim:

The ornamental design for a scarf holder or similar article, as shown.

GUY H. MONTMARTIN.
